UNITED STATES PATENT OFFICE.

JOHN M. WELCH, OF HOUSTON, TEXAS.

SWIMMING BELT.

Application filed October 2, 1923, Serial No. 666,082. Renewed April 26, 1926.

My invention relates to swimming belts, or belts of a similar nature, to be used for pleasure or as life preservers.

It is an object of my invention to construct 5 a belt for swimming or lifesaving purposes which will fit securely about the wearer's waist, and be of flattened shape, lying close to the body of the wearer so that it will not interfere with the motions of the wearer's 10 hands and feet.

It is another object to provide a swimming belt which will be light and which may be rolled up and retained in a small package, easily stored or carried, ready for service.

15 It is another object to provide convenient means for adjusting the length of the belt to conform to the waist measurement of the wearer.

Another object is to provide a means of 20 constructing my improved swimming belt which will make the construction thereof simple and easy of performance.

Referring to the drawings herewith, wherein like numerals of reference are applied to 25 like parts in all the views, Fig. 1 is a front perspective view of a belt embodying my invention; Fig. 2 is a broken front elevation showing a modified form of adjusting means; Fig. 3 is a transverse section of the 30 belt; Fig. 4 is a broken perspective view illustrating one means for forming the partitions in the belt, and Fig. 5 is a transverse section of a belt showing a second means for forming the same.

35 My belt consists of a flattened tube of fabric, impregnated with rubber or similar material impervious to air or water. There are two flattened lengths of the said rubberized fabric, having the edges overlapping at the 40 sides and cemented together to form one continuous tube. It is important to form the inner section 1 of the belt of fabric cut on the bias. This fabric, when stuck to a rubber lining or when impregnated with rubber, is 45 stretched longitudinally thereof so that it will not wrinkle when rolled or secured to the waist of the wearer. The outer section 2 is of a straight strip of rubberized fabric and is best secured over the inturned edges 50 of the inner section 1, as shown in Figs. 3 and 5. The overlapping edges are cemented firmly together. When thus formed, the inner section 1 will conform to the shape of the wearer's waist and will be entirely free 55 of wrinkles or folds when thus in use, and may also be rolled up into a neat package

without causing wrinkles or folds to appear. Cracking of the pneumatic tube will be thus prevented and the belt will last for long periods. The outer section 2 will be approxi- 60 mately flat and will be held thus by partitions in the belt which will be presently described.

In order to prevent the tube from being rounded out as would a vehicle tire when it 65 is inflated, I have formed two partitions 3, cemented at their edges at 4 to the upper and lower sides 1 and 2 of the belt. These longitudinal partitions thus formed serve to hold the opposite sides of the belt from being 70 bowed out when inflated, and thus tend to hold the belt in a flattened shape, as shown in Fig. 3. One end of the belt thus formed is closed and cemented together so that there may be no outlet for the air. The opposite 75 end is closed at a point beyond the ends of the longitudinal partitions 3, except for a small opening 5 at one side thereof, in which is tightly cemented a tube 6 by means of which air may be introduced into the belt. 80 The air thus introduced at the end of the belt may find an entrance to any of the three chambers of the belt and will serve to inflate each portion of the belt uniformly. The end of the inflating tube 6 may be provided with 85 a valve 7, allowing air to be forced into the belt, but preventing its outlet therefrom. This tube may preferably be formed of sufficient length to make it possible for the wearer to easily inflate it when it is buckled 90 on, and under ordinary conditions sufficient air may be blown into the belt by the wearer without the use of an air pump.

The attaching ends of the belt thus formed may be secured together by any adjustable 95 means, and in Fig. 1, I have shown one such means. I have shown on one end of the belt a series of transverse flaps or pleats 8, provided with a plurality of buttonholes 9 therein, these buttonholes being arranged in 100 proper spaced relation from each other to align with a series of buckles 10, upon the adjacent opposite end of the belt. Small straps 11 having buttons 12 on one end thereof are provided, the other end of the 105 strap being preferably reinforced by a strip of metal 13 clamped thereon to prevent wear on the strap. As will be noted, one end of each of these straps may be buttoned in any one of the plurality of flaps or strips 8 and the opposite end thereof may be secured 110 by means of the buckle to the other end of

the belt. In Fig. 1 the two upper straps 11 are shown as secured within the end flap and buckled in position. The lower strap is secured within the second flap and is unbuckled. This arrangement is made to show the adjustability of the straps 11. In use all three straps will be buttoned to the same flap.

In Fig. 2 is shown a modified form of attaching means, the flaps 8' being formed with eyelets 14 therein, there being a similar flap on the opposite end of the belt, and it is contemplated that a lace or string 15 may be secured within the eyelets, as shown, to connect the end 16 of the belt with the opposite end 17 through the eyelets in any of the three flaps 8'. Each opposite pair of eyelets may be provided with a separate lace if so desired.

In forming this type of belt, it is difficult to secure the longitudinal strips of reinforcing material 3 properly in position. I have contrived a means by which the said strips may be properly placed and cemented. In Fig. 4 I have shown three narrow strips of material which may be of wood or metal or some light composition. The central piece 18 has, on each longitudinal side thereof, a tongue or tenon 19, considerably narrower than the thickness of the body portion of the strip. These lateral tongues are adapted to fit very loosely within grooves 20 in the two sides pieces 21. The outer sides of the pieces 21 are rounded at 22, as shown in the drawing. The tongue 19 fits loosely in the groove 20 to allow the fitting around the said tongue throughout the length of the strip, a piece of fabric 3. This fabric, which is cut on the bias, overlaps the central portion a suitable distance and has on the exposed portion thereof, rubber cement or other similar adhering material, adapted to secure the strip to the sides of the belt, as is shown in Fig. 3. When the fabric has been secured along the strips 18 and 21, as shown in Fig. 4, it is inserted within the belt, and when thus inserted, the three assembled strips of material fit closely in the belt. This may be done while the tube is being formed, as previously described, or may even be done when the tube has been partly formed. The upper and lower sides may then be pressed firmly down against the exposed sides of the strip 3, and thus cemented in place; and when the cement has properly set, the strips 18 and 21 may be withdrawn. This will be readily accomplished by moving the side strips 21 slightly away from the central portion, so as to allow the withdrawal of first one and then the others in succession. When the parts have been thus secured together longitudinally, the ends may be sealed, as previously described.

In Fig. 5 I have shown a second means of

cementing the partitions in position. In this embodiment I provide three longitudinal strips of material, which may be of wood, or some other like composition, there being a central piece 18' and two lateral strips 21'. The two strips 21' are rounded at their outer edges at 22', but the inner ends are flattened to fit closely against the adjacent sides of the central strip 18'. A piece of bias fabric material 3' is wound about the central strip with the two edges thereof meeting on the upper face at 23. The two side blocks are then placed in position, and the exposed upper and lower sides of the reinforcing fabric are covered with cement and the assembled core thus formed is inserted within the tire, and the cement allowed to set in contact with the upper and lower sides of the belt, after which the strips 18' and 21' are withdrawn. As will be obvious, these partitions may best be inserted while the tube is being formed. The partition being of bias material may be folded without wrinkling.

The advantages of this type of construction lie in the fact that the belt may, when deflated, be folded or rolled into a small package, easily stored or carried. The belt may, when inflated, be easily secured about the waist, will fit the waist line of the wearer and will not in any way interfere with his motions in swimming. A small amount of air in the belt will be sufficient to sustain the swimmer under all conditions. The device is easily secured in place, and is light and convenient.

Having thus described my invention, what I claim as new and desire to protect by Letters Patent is:

1. A pneumatic life belt comprising, an inner wall of fabric cut on the bias and stretched longitudinally and formed impervious to water or air, its edges being folded forwardly, an outer wall of similar material not cut on the bias and secured to the folded edges of said inner wall, means to prevent distension of the said walls, said walls being sealed to form a tube and means to allow inflation of said tube.

2. A pneumatic life belt comprising an inner wall of rubberized fabric, cut on the bias, an outer wall of rubberized fabric, said walls being sealed at their adjacent edges to form a tube, and means to inflate said tube.

3. A pneumatic life belt comprising an inner wall of bias fabric, and an outer wall of a flattened strip of fabric, said walls being impervious to water or air, means to limit the distance between said walls and means to allow inflation of said belt.

4. In a pneumatic life belt, an inner wall of bias fabric, an outer wall of fabric, means to limit the distance between said walls and means to allow inflation of said belt.

5. In a life belt, a pneumatic tube, means

to limit the thickness of said tube when inflated, and means to secure the ends of said tube together comprising straps having adjustable attachment to one end of said belt, and cooperating buckles on the opposite end of said belt for the purpose described.

6. In a life belt, a pneumatic tube, means to allow inflation thereof and means to secure said belt in position, comprising a plurality of flaps on one end of said belt, attaching means secured adjustably to any one of said flaps, and cooperating attaching means on the opposite end of said belt.

7. A pneumatic life belt comprising a

front section and a back section, the material of the back section having a greater degree of yieldability than the material of the front section.

8. A pneumatic life belt comprising a front section and a back section, the material of one of said sections being cut on the bias to permit a greater degree of yieldability therein than in the other of said sections.

In testimony whereof, I hereunto affix my signature this the 31 day of August, A. D. 1923.

JOHN M. WELCH.
